[57] CLAIM

The ornamental design for a furniture leg, as shown and described.

DESCRIPTION

FIG. 1 is a perspective view of a furniture leg, showing my new design;

FIG. 2 is a front elevational view thereof;

FIG. 3 is a left side elevational view thereof, the right side being a mirror image;

FIG. 4 is a top plan view thereof;

FIG. 5 is a bottom plan view thereof; and

FIG. 6 is a rear elevational view thereof.

FIGS. 2-6 have been drawn to a reduced scale with respect to FIG. 1.
